(57) **CLAIM**

The ornamental design for a soffit mounting device, as shown and described.

DESCRIPTION

FIG. 1 is a front, top, left perspective view of a first embodiment of a soffit mounting device embodying our new design;

FIG. 2 is a front elevation view of the first embodiment of a soffit mounting device embodying our new design;

FIG. 3 is a rear elevation view of the first embodiment of a soffit mounting device embodying our new design;

FIG. 4 is a left side profile view of the first embodiment of a soffit mounting device embodying our new design, the right side being a mirror thereof;

FIG. 5 is a top plan view of the first embodiment of a soffit mounting device embodying our new design;

FIG. 6 is a bottom plan view of the first embodiment of a soffit mounting device embodying our new design;

FIG. 7 is a front, top, left perspective view of a second embodiment of a soffit mounting device embodying our new design;

FIG. 8 is a front elevation view of the second embodiment of a soffit mounting device embodying our new design;

FIG. 9 is a rear elevation view of the second embodiment of a soffit mounting device embodying our new design;

FIG. 10 is a left side profile view of the second embodiment of a soffit mounting device embodying our new design, the right side being a mirror thereof;

FIG. 11 is a top plan view of the second embodiment of a soffit mounting device embodying our new design; and,

FIG. 12 is a bottom plan view of the second embodiment of a soffit mounting device embodying our new design.

The drawings contain a symbolic break indicated in dash-dot broken lines. The portion between the break lines forms no part of the claimed design.

1 Claim, 6 Drawing Sheets
